UNITED STATES PATENT OFFICE.

PATRICK J. RILEY, OF CLEVELAND, OHIO.

OIL CONTAINER AND PUMP.

Application filed March 20, 1926, Serial No. 96,243. Renewed May 19, 1927.

The present invention relates to grease and oil containers of the character having a pump therein for dispensing the contents of the container; however, the invention is the provision of such a device which is capable of being shipped in a filled condition without being crated, the head of the drum or container being so constructed as to permit parts of the pump, normally arranged outside of the drum, disassembled and to be packed in the head of the drum without projecting beyond the confines of the side walls of the drum.

It is the further object of the invention to produce a device of the above stated character in an extremely simple and economical manner which will eliminate crating, save storage space, and which utilizes only the parts of the device itself for maintaining the parts in shipping condition.

With the above objects in view, the invention further resides in the sundry details of construction, combination and arrangement of parts hereinafter more fully described and pointed out in the appending claims.

In this specification and the annexed drawings, the invention is disclosed in the form in which it is considered to be the best, but the invention is not limited to such form because it is capable of being embodied in other forms, and it is understood that by and in the claims following the description herein, it is intended to cover the invention in whatever form it may embody within the scope thereof.

In the drawings which show the preferred embodiment as at present devised;

Figure 1 is a vertical sectional view of an oil and grease drum or container having the construction and assemblage of this invention;

Figure 2 is a plan view of the drum showing Figure 1 with the parts assembled for shipment; and

Figure 3 is a fragmentary vertical sectional view taken on line 3—3 of Figure 2.

Throughout the specification and drawings like characters of reference denote similar and like parts of the invention and structure shown.

With particular reference to the drawings, 10 denotes a barrel or drum, usually of metal, as is commonly used in connection with the shipment and dispensing of grease and oils, the drum being closed at its ends by

the heads 11 and 12 and there also being usually an upstanding rib or flange 13 extending beyond the head. For the purposes of convenience in this specification, whenever the term "head" is referred to herein, the upper or top wall 12 is meant and whenever the term "bottom" is used, the head 11 is referred to.

It is commonly the practice in connection with lubricants to provide an opening at the top wall of the drum containing the same and to insert a pump which may loosely extend into the container, or to permanently attach to the drum and in an opening of the head, a pump. In the latter case, however, the piston rod and portion of the pump barrel project beyond the head of the drum as well as the operating handle and other exterior parts of the pump. This necessitates the drum to be crated in order to protect the pump and the head of the drum during shipment. Such crate is expensive and increases the area occupied by the drum in storage, as well as the difficulty in handling the drum during shipment.

By the present invention the above drawbacks are overcome by providing a head plate or cover 14 having its central portion depressed, as at 15 to form a pocket or chamber which will extend into an opening provided in the top head 12 of the drum. The marginal portion *b* of the head plate rests on the head 12 and is provided with suitable openings which register the corresponding openings in the head for receiving the bolts 15 holding the parts together. The head plate 14 has mounted thereon the pump unit P so that it may be removed and placed into the drum by the removal or application of the plate 14 to the drum.

The pump unit consists of a barrel or cylinder 16 connected with a reducer or cap 17. The reducer 17 extends through an opening in the center of the depression *a* of the head plate and has an abutment 18 to rest thereagainst, the top of the cylinder being threaded into the reducer and a lock-nut 19 being threaded on the reducer to tightly bind the edge of the opening of the top plate 100 between it and the abutment 18. The cylinder 16 extends downwardly to a point adjacent the bottom wall of the drum and has threaded therein a T-joint or coupling 20, the intermediate arm *c* of the T-joint being connected with an upwardly extending discharge pipe 21 projecting through an open-

ing in the depression *a* of the head-plate, as clearly shown in the drawings. The end of the pipe 21 extending through the head plate carries a suitable coupling 22 to which a hose 23 or the like may be detachably connected. The other arm of the T-joint 20 has a nipple 24 threaded therein which normally rests on the bottom 11 of the drum, the nipple being provided with openings 25 for admitting grease and oil into the cylinder of the pump. A ball valve 26 is disposed in the T-joint 20 and normally rests upon and co-operates with the upper end of the nipple 24 for the purpose of closing the inlet end of the pump when the piston 27 is being actuated to force the contents from the cylinder 16 out through the discharge pipe 21. The opening or upward movement of the ball valve 26 is limited by a stop pin 28 positioned a suitable distance above the nipple 24.

The piston 27 is of the usual construction and has a piston rod 29 extending upwardly through the reducer or cap 17, at which point in the latter a stuffing gland is provided.

A hand lever 31 is fulcrumed on a supporting link 32 pivotally mounted at 33 on a cleat or base member 34. This cleat or base member is designed to rest upon the marginal portion *b* of the head plate 14 and has an opening 35 therein to register with the openings which receive the bolts 15, whereby the cleat may be secured in position by one of said bolts which secure the head plate on the drum as clearly shown in Figure 1. The forward end of the cleat is, however, provided with a downwardly projecting lip 36 to extend over around the edge of the depressed portion *a* of the head plate so as to give additional stability to the cleat, when in operative position as shown in Figure 1. When the upper end of the piston rod 29 is connected with the operating handle 31 as shown at 37, the piston may be reciprocated in a manner to discharge the contents of the drum as is manifest.

From the foregoing, it is apparent that the depression *a* in the head plate provides a pocket or chamber of sufficient depth to retain the reducer or cap 17 within the confines of the drum and without extending beyond the upper edge of the same. Thus, it will be seen that when it is desired to ship the drum, it is only necessary to coil the hose 23 within the chamber or depression *a* and to disconnect the cleat 34 from its position shown in Figure 1, by removing the bolt 15, and to disconnect the piston rod from the handle 31, at the point 37. The piston rod 29 is then moved its full length into the cylinder and the upper end of the reducer closed with a removable cap 38. The operating handle is then laid across the top of the drum in the fashion indicated in Figures 2 and 3, with the lever portion 31 extending across the

chamber or pocket *a* in one direction and the supporting link 32 extending across the chamber or pocket *a* in another direction, there being openings 39 and 40 in the handle 31 and link 32, respectively, through each of which, one of the head-plate securing bolts 15 may be extended for holding the handle in position in the chamber *a* below the edge of the flange 13. It will also be observed that by so positioning the handle across the pocket *a*, the hose 23 is retained in position during shipment.

From the above it will be observed that a very economical and practical improvement has been made in shipping and storage vessels permitting the same to be shipped with a pump permanently attached thereto without requiring crating and without any of the operating parts and parts of the pump structure whereby the vessels may be stored in close relation and one upon another without intruding beyond the confines of the vessel, certain of the disassembled parts being arranged and secured within the confines of its vessel for retaining other parts in shipping position.

Having thus described the invention, what is claimed is:

1. In a shipping and storage vessel, a drum having a pump located therein, external pump handle and hose normally connected with the pump, when the parts are in operative position, and detachable therefrom; said drum being provided with an external chamber capable of receiving said hose for storage, within the confines of said drum; said handle being shaped to lie across said chamber, when disconnected, for maintaining said hose in said chamber for shipping purposes, and means for detachably securing said handle in stored position.

2. In a shipping and storage vessel, a drum having a pump located therein; external handle and hose normally connected with the pump, when the parts are in operative position, and detachable therefrom, a head plate at one end spaced from the end edge thereof for providing a chamber capable of receiving said hose and handle for storage within the confines of the drum when disconnected from said pump; said handle being shaped to lie across said chamber in stored position, when disconnected for maintaining said hose in said chamber for shipping purposes; and means for detachably securing said handle in stored position.

3. In a shipping and storage vessel, a drum having a pump located therein; external pump handle, handle-supporting link and hose normally connected with the pump and drum, when the parts are in operative position, and detachable therefrom; a head at one end of the drum spaced from the end edge thereof and having a depression therein capable of receiving said hose or other

- elements for storage, said handle and handle supporting link being so shaped and connected together as to permit them to lie across said depression in the head in substantially triangular form when detached from operative position; and means for detachably securing said handle and support to the head to maintain said elements in stored position for shipping purposes and 10 within the confines of the drum.
4. In a shipping and storage vessel, a drum having a pump located therein; external pump handle, handle-supporting link and hose normally connected with the pump and drum, when the parts are in operative position, and detachable therefrom; a removable head at one end and spaced from the end edge thereof and formed with a depression therein capable of receiving said 15 nose and other elements for storage; fastening elements for detachably securing said head to the drum; said handle and support being so shaped and connected together to permit them to extend across said depression, in substantially triangular form when detached from operative position for retaining the elements in said depression therein, and means on said handle and support engageable by said head fastening elements for detachably retaining same in stored position within the confines of the drum.
5. In a shipping and storage vessel, a drum having a head, fastening means removably securing said head in position to the drum; said head having a depression therein to extend in said head-opening; a pump mounted on the wall of said depression in said plate and extending in said drum; a discharge pipe connected with the pump and extending through the wall of said depression; a hose connected to said pipe and capable of being stored in said depression; external pump handle detachably connected with the pump; said handle including a handle support detachably connected to the head by said fastening means and being shaped to lie on said head plate and across said depression in stored position within the confines of the drum, when disconnected; and means for retaining said handle in said stored position whereby said hose may be retained in said stored position for shipping.
6. In a shipping and storage vessel, a drum having a head at one end spaced from the end edge thereof; said head having an opening therein; a head-plate having a central depression therein extending in said head opening, bolts extending through the marginal portion of said plate and said head for removably securing the plate in position, a pump mounted on said plate extending into said drum and projecting through said depressed portion; external handle and hose connected with the pump, said handle including a supporting link detachably connected to the head-plate by said bolts, said hose capable of being stored in said depression, said handle and link being adapted to lie on said head-plate and across said depression within the confines of said drum; said handle having means engageable by said bolts whereby it may be secured in said stored position and retains said other elements in said stored position.
7. In a shipping and storage vessel, a dispensing drum, a head at one end of the drum, fastening means for removably securing the head in position on the drum, there being a space between the end of the drum and said head forming a chamber, a plurality of elements mounted externally on the drum and adapted to project beyond the confines when dispensing the contents of the drum thereof, said elements being adapted to be received in said chamber for storage purposes, certain of said elements being detachable from the drum and being substantially elongated and adapted to overlie said chamber when disconnected and to retain said other elements therein, said elongated elements also being constructed for engagement by said head, fastening means, when said elements are so disconnected and arranged, whereby said elements may be maintained in stored position.

In testimony whereof I have hereunto set my hand.

PATRICK J. RILEY.
